UNITED STATES PATENT OFFICE.

THOMAS J. L. SMILEY AND CHARLES H. STOMBS, OF SAN FRANCISCO, CAL.

AUTOMATIC LAMP-EXTINGUISHER AND WICK-TRIMMER.

SPECIFICATION forming part of Letters Patent No. 290,607, dated December 18, 1883.

Application filed May 21, 1883. (Model.)

To all whom it may concern:

Be it known that we, THOMAS J. L. SMILEY and CHARLES H. STOMBS, both of San Francisco, in the county of San Francisco and State 5 of California, have invented a new and Improved Automatic Lamp-Extinguisher and Wick-Trimmer, of which the following is a full, clear, and exact description.

Our invention relates to automatic lamp-extinguishers and wick-trimmers; and it consists 10 in the peculiar construction and arrangement of the parts, as hereinafter more fully set forth, and pointed out in the claims.

Reference is to be had to the accompanying 15 drawings, forming part of this specification, in which similar letters of reference indicate corresponding parts in all the figures.

Figure 1 is a side elevation of a wick-tube on which a pair of extinguishing claw-plates 20 are pivoted to a removable support adapted to be fitted on the wick-tube, so that the wick will have power to open them when thrust up by the wick-adjuster, and which will fall together by gravity or spring-pressure over the 25 wick and extinguish it when the wick is pulled down. Fig. 2 is a sectional elevation of Fig. 1 on line *x x*. Fig. 3 is a side elevation of a modified form of the device represented in Figs. 1 and 2, and Fig. 4 is a section of Fig. 3 30 on line *w w*.

We propose to have two plates, *a*, to close over the wick-tube *b* by turning on pivots *c*, as in Figs. 1 and 2, or to spring over the tube, as in Figs. 3 and 4, inclusive. When the 35 plates *a*, pivoted at *c* in the removable support, are employed, the distance from the pivotal point *c* to the upper end of each plate *a* is greater than from the pivotal point *c* to the lower end of each plate *a*, so that when the

wick-tube is held vertical (its normal position 40 when in use) the upper ends of the plates *a*, above their hinges, will be heavier than their lower ends below their pivotal points *c*, and when the wick is drawn down by the wick-adjuster below the plates *a*, the latter will fall 45 on the upper end of the wick-tube by gravity, extinguish the light, and trim the wick, and both these results are obtained automatically.

In the arrangement of Fig. 1 the plates are 50 opened by the push of the wick against them when it is raised by the ratchet, and they close by gravity when the wick is lowered.

Having thus described our invention, we 55 claim as new and desire to secure by Letters Patent—

1. The combination, with a wick-tube, of a removable frame provided with an aperture to receive said tube, and carrying plates which are adapted to be opened by the wick in raising it, and so pivoted to the frame as to fall 60 by gravity, whereby they are automatically closed when the wick is lowered, substantially as shown and described, whereby the lamp is automatically extinguished and trimmed, as set forth. 65

2. An improved article of manufacture, consisting of a frame provided with an aperture adapted to fit over a lamp-wick tube, and provided with plates *a*, so pivoted to said frame as to fall by gravity, whereby they are automatically closed when the wick is lowered, 70 substantially as set forth.

THOMAS J. L. SMILEY.
CHAS. H. STOMBS.
